CAR TRUCK

Alfred H. Oelkers, New Braunfels, Tex., assignor
to American Steel Foundries, Chicago, Ill., a
corporation of New Jersey

Application July 21, 1941, Serial No. 403,332

24 Claims. (Cl. 105—197.1)

My invention concerns railway car trucks and more particularly a four wheel freight car truck utilizing truss side frames and a connecting bolster.

My present invention consists of an improved form of four wheel railway car truck wherein each truss side frame comprises a compression member, a tension member, and spaced columns defining with said members a central bolster opening and spaced window openings. Each tension member below the bolster opening is a U-section affording seats for a plurality of coil springs and on said coil springs may be superposed plate springs extending across the bolster opening with their ends projecting through aligned openings in the columns at opposite sides of the bolster opening, each of said ends being seated on a vertically slideable block or spring plate supported at an intermediate point on the tension member.

Generally, the object of my invention is to devise an improvement in a well-known form of four wheel freight car truck whose principal identifying characteristic consists of a bolster structure having a bifurcated end portion which may seat at spaced points on a semi-elliptic spring which, in turn, may be superposed on a plurality of coil springs so that the leaves of the semi-elliptic spring are squeezed between the superposed load and the supporting coil springs. The general form of this truck is set forth in my previous Patent No. 2,051,649, issued by the United States Patent Office August 18, 1936.

My present application illustrates an improved form of such truck wherein the semi-elliptic or flat plate springs are supported within a truss type side frame and the ends of said leaf springs are slidably supported in the diagonal portions of the tension member of each side frame on abutment blocks serving also as spring caps, said blocks being supported on coil springs.

In my present novel arrangement, I may utilize a plate spring structure made up of a plurality of spring bars of identical size and shape which are maintained in proper relationship with each other to perform the function of a semi-elliptic or leaf spring without the use of a spring band and without the necessity of arching or otherwise forming the individual spring leaves. The advantages resulting from such simplicity will be apparent.

It may be noted also that with the structure described herein I have afforded a considerably longer spring travel without overstressing the leaf springs or working them under a longer

stress range than would be desirable. This I have accomplished by supporting the leaf springs not only at intermediate points on the coil springs but also at the extremities of the leaves.

5 Thus, the range of fiber stress to which the leaves may be subjected in service is controlled by the relative stiffness of the coil springs supporting the leaves and this may be modified as desired to meet varying conditions. By this means, I 10 may control the total flexure of the leaf springs and, at the same time, accommodate varying conditions of bolster travelling requirements.

A specific object of my invention is to devise 15 a novel form of truss type side frame particularly adapted for the type of freight car truck herein illustrated.

My invention comprehends a novel form of 20 truss type side frame wherein spaced columns are afforded inboard and outboard portions with 25 openings aligned longitudinally of the frame between the column portions for accommodation of an associated plate spring and wherein each tension member is afforded a cavity intermediate the wheel connecting portion and the adjacent column which may house a coil spring for support of one end of said plate spring. My novel side frame structure may afford abutment means adjacent said last-mentioned spring seat for an 30 associated slideable spring cap.

35 My novel side frame structure comprehends an arrangement wherein the upper portion of each column may serve as a guide surface for the adjacent bolster and the upper portions of said columns affording a substantially flat surface for that purpose extending entirely across the frame while the intermediate portion of the column is cut away, as already described, to accommodate a series of plate springs extending therethrough, the opening in each of said columns closely confining the side edges of said spring to a vertical up and down movement consistent with the normal operation of the truck.

40 In my novel form of side frame, the tension 45 member is substantially of U-section from one end of the frame to the other, said U-section having its greatest depth intermediate the journal box and the adjacent columns where an auxiliary spring seat is afforded at each end of the frame. The shallowest portion of the U-section is beneath the bolster opening, and on the bottom web of said U-section may be afforded a plurality of seats for coil springs on which may be superposed the plate springs.

50 In the drawings, Figure 1 is a side elevation

of a railway car truck structure embodying my invention.

Figure 2 is a half top plan view thereof, only one-half of the truck being shown inasmuch as the arrangement is similar at both sides thereof.

Figure 3 is a sectional view taken substantially in the transverse vertical plane bisecting the truck and as indicated by the line 3-3 of Figure 1, a portion of the bolster being shown in side elevation.

Figures 4, 5, 6, and 7 show in detail my novel form of side frame, Figure 4 being a side elevation thereof with only one end of the structure shown since it is similar at opposite ends, Figure 5 being a fragmentary top plan view thereof, Figure 6 a fragmentary bottom plan view, and Figure 7 a sectional view taken substantially in the transverse vertical plane bisecting the frame as indicated by the line 7-7 of Figure 4.

My novel truck structure utilizes spaced truss type side frames of identical form each having a compression member 2 of inverted U-section, a tension member 4 of U-section, and spaced columns 6, 6 merging with said members to form a central bolster opening 8 and spaced window openings 10, 10, said members also converging adjacent the ends of the frame and merging with integrally formed journal boxes 12, 12 forming a conventional means of connection to the journal ends of spaced wheel and axle assemblies 14, 14. At the upper part of each column and on the inboard side of each frame may be formed the usual brake hanger brackets 16, 16 (Figure 2).

Extending within the bolster opening 8 may be the end portion of the bolster generally designated 18, said bolster having a center bearing 20 and a side bearing 22 together with the brake beam guard angle iron 24 supported as at 26 (Figure 3) from a bracket depending centrally from the bottom of said bolster. The central body portion of the bolster 18 may be of conventional box structure, and each end of the bolster is bifurcated following a well-known form, each leg of the bifurcated end portion being designed as a downturned jaw designated 28 for fixing the position of the bolster 18 with respect to the supporting plate spring assembly generally designated 29. The outboard portion of each jaw 28 has a depth A (Figure 3) somewhat less than the clearance B above the top of the bolster and the bottom of the compression member 2 thereabove so that said bolster end may be elevated above the spring structure on which it is seated and removed from the bolster opening 8 without disturbing said spring structure. The inboard portion of each jaw 28 affords abutment for the inner edge of the plate spring assembly 29, said inboard abutment extending for substantially the depth of said spring and having a depending lug 30 extending still further and so positioned as to be intermediate adjacent coil springs, said lugs 30 affording bearing against the inboard edge of the spring assembly for an additional depth which may be desirable when the bolster is shimmed in customary manner by insertion of a shim plate as at 32 within said bolster jaws and on top of the spring assembly 29. It may be noted that the bearing of each bolster jaw upon the spring assembly is concentrated at the edge of the jaw nearest the transverse center line of the truck, the bearing surface on the bolster being arcuately relieved therefrom as may be noted at 34, 34 (Figure 1), thus permitting increased bearing area and shortening of the lever arm as the load is increased. When the

spring assembly is depressed, the area of bearing of the bolster end upon the top plate spring 29 is increased and reaches a maximum when the said spring is depressed to its utmost.

5 The plate spring assembly 29 comprises a plurality of flat plate springs without camber superposed one above the other, and said plate springs are not secured in assembly by any spring band or other means but are retained in their normal 10 assembled relationship solely by the manner in which they are assembled between the inboard and outboard portions of the spaced columns of the side frame, the manner in which their end portions are supported on the slidable abutment 15 blocks or spring caps 36, 36, and further by the squeezing action of the intermediate group of coil springs 38, 38, each of said coil springs 38 having its low end recessed in the U-section tension member and positioned therein by upright 20 studs 40, 40. The detailed form of each end abutment block or spring cap 36 may be seen from a consideration of the top plan view of Figure 2 and the side elevation of Figure 1. Said block consists of inboard and outboard side walls 25 42, 42 merging with a rear or transverse wall 44, said transverse wall having the spaced vertical flanges 46, 46 which may have slidable engagement as at 48 against the vertical transverse web 50 formed as an integral portion of the tension 30 member and extending between the inboard and outboard walls thereof. The base portion of each end block 36 is formed as a substantially rectangular plate having on its bottom face 35 spring positioning means 52 for the adjacent end coil spring 54, the bottom of said coil spring being seated as at 56 on the bottom web of the tension member therebelow and positioned thereon by the upstanding lug 58. The transverse web of the tension member is formed at this point 40 with a substantially horizontal portion, and at the outer edge of said horizontal portion said web turns sharply upwardly to merge as at 60 with the lower inner corner of the adjacent journal box. Each spring cap or end block 36 thus 45 affords a seat as at 62 for the adjacent end of the spring assembly 29, and the seat on the block for said spring assembly may be arcuately relieved as at 64 (Figure 1) so that the lever arm may be steadily shortened as the load is increased 50 due to the arcuate bearing areas at 64 and 34. The side walls of each bearing block 36 may have 55 slidable engagement with the inboard and outboard vertical webs of the tension member which may be increased somewhat in depth therealong as at 66 in order to afford more complete bearing area for said side walls.

My novel side frame structure is shown in detail in Figures 4 to 7 inclusive. I have already stated the side frame is of truss type having the compression member 2 of general inverted U-section having a top web 68, a downturned outboard web 70, and an inboard web 72. The structure of the compression member is reinforced by the rib 74 extending transversely thereof at the middle of the frame, as well as by a rib 76 above each window opening 10 and by the transverse wall 78 at the top of each column which affords bearing area for the adjacent side wall of the bolster end. The vertical wall 78 is continuous at its upper end with a horizontal portion 79, and between the columns, the inboard and outboard webs 70 and 72 of the compression member are reflanged as at 81, 81 to further reinforce said member. Each transverse wall 78 at 70 the top of the column is cored away centrally 75

thereof as at 80 in a rectangular opening, the inboard and outboard edges of which at 82, 82 (Figure 7) afford positioning means for the before-mentioned plate spring assembly 29 which extends therebetween and said plate springs may have frictional engagement with said edges 82, 82 under certain conditions of relative movement of the bolster with respect to the side frames, thus affording some damping action.

The top web 68 of the compression member is continuous from end to end of the frame terminating in an arcuate edge 84 above the inner wall of the adjacent journal box and affording clearance at each end therefor above said journal box to permit the application, or removal thereover of the plates of the spring assembly 29, said plates being unconfined with respect to one another so that they may be handled singly thus facilitating their application and removal while at the same time reducing to a single form of spring plate the stock requirements which must be on hand for repair purposes.

Each column 6 is U-section along its upper portion and to the upper edge of the cored opening 89, each column therebelow having an L-section as at 88 (Figure 7) along its midportion, the transverse flanges of which terminate as at 88, 88 so that therebelow each column is a simple wall structure reinforced along its outboard edges by beaded portions as at 99 and 92. The bolster guide surface on each column therefor extends from the top of the bolster opening 8 downwardly to the ledges or shoulders at 88. Below the shoulders 88, the window opening 10 has maximum width as may be noted at 94 thus permitting substantially full inspection of the coil springs which are seated in the tension member below said opening.

The tension member 4 is of U-section from end to end, the section having its shallowest portion beneath the bolster opening 8 and comprising there, as elsewhere, a bottom web 96, an inboard vertical wall or web 98, and an outboard wall 100 with a plurality of vertical ribs 102 extending between said walls intermediate the coil spring seats formed at the bottom of said window opening. The transverse web 96 of the tension member affords said spring seats as at 104, 104, and each of said spring seats may have a lug 40 serving to position the coil springs which may be seated thereon. Substantially beneath each column the web 96 may be cored away in an opening 108 to permit escape of water or other extraneous matter, and above said opening and at the base of each column may be formed at the top of the tension member a transverse web 110 (Figure 7) serving to reinforce the side frame structure in this vital area, said web 110 extending along the bottom of the window opening 10 and terminating as at 112 adjacent the lower extremity of the upright wing portion 66 formed as a continuation of each inboard and outboard web of the tension member to enclose the spring cap and abutment block which may be positioned therebetween as already described. The upper end of the wing portion 66 may terminate as at 116 (Figure 4) immediately above the transverse web 50 which extends between the inboard and outboard walls of the tension member and affords with said walls a housing or pocket 117 for the spring cap and abutment block which may have vertical sliding movement therealong. Each wall of the tension member within the pocket thus

formed has a raised portion as at 118, 118 (Figure 6) which may be machined or otherwise formed smooth and true to afford abutment for the side walls of the enclosed spring cap 36 as already described, said raised portions being in substantial alignment with the before-mentioned abutment means 82, 82 on the columns and also serving as guiding means for the spring assembly 29 confined therebetween. Immediately below the pocket 117, the transverse web 96 of the tension member may be formed with a horizontal portion defining the spring seat 120 and on said seat may be formed the spring positioning means 58, the web 96 turning upwardly from the edge of the spring seat 120 to merge as at 60 with the inner lower edge of the adjacent journal box. Thus, the inboard and outboard webs 98 and 100 of the tension member have their greatest depth in the vicinity of the spring seat 120 and the pocket 117, said side walls having in this area a depth substantially twice that at the midportion of the frame and so accommodating a coil spring assembly which may be seated on the spring seat 120 and afford support for the superposed slidably abutment means and spring cap which may be housed in the pocket 117 as already described. Each side wall of the tension member in the vicinity of said end spring assembly may be cored away as at 126 to permit inspection of the springs housed therein.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claims.

40 I claim:

1. In a railway car truck, a side frame having upper and lower members and spaced columns forming therewith a bolster opening and spaced window openings, coil springs seated on said lower member beneath said window openings adjacent opposite ends of the frame, spring caps slidably engaged with said lower member and seated on said springs, other coil springs supported on said lower member below said bolster opening, a plate spring assembly supported on said coil springs in said bolster opening with the extremities thereof seated on said caps, and a bolster supported on said plate spring assembly in said bolster opening in guiding engagement with said columns, said bolster having downturned jaw means engaging the outboard and inboard edges of said plate spring assembly, and the outboard portions of said jaw means having a depth less than the clearance between said compression member and the top of said bolster to permit removal of said bolster from said bolster opening while said plate spring assembly remains in normal operating position.

2. A truss side frame having tension and compression members merging adjacent their ends with integral journal boxes, spaced columns forming with said members a bolster opening and spaced window openings, said compression member having an inverted U-section and said tension member having a U-section with maximum depth adjacent said journal boxes, transverse webs extending between the inboard and outboard walls of said tension member adjacent said boxes to define with said walls pockets for associated spring caps slidably positioned there-

in, spring seats on the bottom chord of said tension member beneath said pockets, and other spring seats on said tension member beneath said bolster opening, all of said spring seats being aligned longitudinally of said frame and said columns having vertical openings aligned longitudinally of said frame and with said pockets to accommodate an associated spring member, each of said columns affording lateral abutment means for said spring member.

3. In a railway car truck of quick wheel change type, a truss side frame having tension and compression members and spaced columns forming therewith a central bolster opening and spaced window openings, coil springs supported on said tension member below each of said openings, a plate spring assembly supported at spaced points on said coil springs, and a bolster having an end projecting into said bolster opening and supported at spaced points on said plate spring assembly, said bolster end having a plurality of downturned jaw means confining said plate spring assembly, the outboard portions of said jaw means having a depth less than the clearance between the top of said bolster end and the overlying portion of said compression member, and the inboard portions of said jaw means being extended below the lowermost of said plate springs to afford abutment therefor when said bolster end is elevated in a shimming operation.

4. In a railway car truck, a side frame comprising tension and compression members and spaced columns merging therewith to form a central bolster opening and spaced window openings, coil springs seated on said tension member below said openings, slideable abutment blocks supported in said tension member on the end coil springs, leaf springs superposed on said intermediate coil springs with their ends supported on said blocks, a bolster having an end extending into said bolster opening in guiding engagement with said columns, said bolster having jaw means embracing said plate spring at spaced points, said jaw means having oppositely tapered areas bearing against said plate springs to permit increased bearing area thereagainst as the superposed load is increased, and each of said blocks having an arcuately tapered seating surface to permit shortening of the lever arm as said plate spring is flexed under load.

5. A truss side frame having tension and compression members merging adjacent their ends with integral journal boxes, spaced columns forming with said members a bolster opening and spaced window openings, said compression member having an inverted U-section and said tension member having a U-section with maximum depth adjacent said journal boxes, transverse webs extending between the inboard and outboard walls of said tension member adjacent said boxes to define with said walls pockets for associated spring caps slidably positioned therein, spring seats on the bottom chord of said tension member beneath said pockets, and other spring seats on said tension member beneath said bolster opening, all of said spring seats being aligned longitudinally of said frame and said columns having vertical openings aligned longitudinally of said frame and with said pockets to accommodate an associated spring member.

6. In a railway car truck of quick wheel change type, a truss side frame having tension and compression members and spaced columns forming therewith a central bolster opening and spaced window openings, coil springs supported on said

tension member below each of said openings, a plate spring assembly supported at spaced points on said coil springs, and a bolster having an end projecting into said bolster opening and supported at spaced points on said plate spring assembly, said bolster end having a plurality of downturned jaw means confining said plate spring assembly, the outboard portions of said jaw means having a depth less than the clearance

5 between the top of said bolster end and the overlying portion of said compression member to permit the removal of said bolster end from said bolster opening while all of said springs remain in assembled relationship with said side frame.

10 7. In a railway car truck, a side frame comprising tension and compression members and spaced columns merging therewith to form a central bolster opening and spaced window openings, coil springs seated on said tension member below said openings, slideable abutment blocks supported in said tension member on the end coil springs, leaf springs superposed on said intermediate coil springs with their ends supported on said blocks, and a bolster having an end extending into said bolster opening in guiding engagement with said columns, said bolster having jaw means embracing said plate springs at spaced points, each of said blocks and each of said jaw means having seating engagement with

20 30 said plate springs along a tapered surface to afford a shortening levering arm as said plate spring is depressed under load.

35 8. In a railway car truck, a side frame comprising tension and compression members and spaced columns merging therewith to form a central bolster opening and spaced window openings, coil springs seated on said tension member below said openings, slideable abutment blocks supported in said tension member on the end coil springs, leaf springs superposed on said intermediate coil springs with their ends supported on said blocks, and a bolster having an end extending into said bolster opening in guiding engagement with said columns, said bolster having jaw means embracing said plate springs at spaced points, said jaw means having oppositely tapered areas bearing against said plate springs to permit increased bearing area thereagainst as the superposed load is increased.

40 9. In a railway car truck, a side frame having upper and lower members and spaced columns forming therewith a bolster opening and spaced window openings, coil springs seated on said lower member beneath said window openings adjacent opposite ends of the frame, spring caps slidably engaged with said lower member and seated on said springs, other coil springs supported on said lower member below said bolster opening, a plate spring assembly supported on

45 55 said coil springs in said bolster opening with the extremities thereof seated on said caps, and a bolster supported at spaced points on said plate spring assembly in said bolster opening, the bearing areas of said bolster on said plate spring assembly being oppositely tapered to afford a shortening lever arm as said plate spring is placed under load.

60 10. A truss side frame having tension and compression members merging adjacent their ends with integral journal boxes, spaced columns forming with said members a bolster opening and spaced window openings, said compression member having an inverted U-section and said tension member having a U-section with maximum depth adjacent said journal boxes,

65 70 75

transverse webs extending between the inboard and outboard walls of said tension member adjacent said boxes to define with said walls pockets for associated spring caps slidably positioned therein, openings in said columns aligned with said pockets, spring seats on the bottom chord of said tension member beneath said pockets, and other spring seats on said tension member beneath said bolster opening.

11. In a railway car truck, a side frame having upper and lower members and spaced columns forming therewith a bolster opening and spaced window openings, coil springs seated on said lower member beneath said window openings adjacent opposite ends of said frame, other coil springs supported on said lower member below said bolster opening, a plate spring assembly supported on said coil springs, and a bolster supported at spaced points on said plate spring assembly in said bolster opening, the bearing areas of said bolster on said assembly being oppositely tapered to afford a shortening lever arm as said assembly is placed under load.

12. In a railway car truck, a side frame comprising a bolster opening, a coil spring group on said frame, a plate spring assembly supported from said group in said opening, said assembly consisting of a plurality of superposed relatively movable plates abutting each other throughout their length, means on said frame for retaining said plates in assembly, and a bolster end mounted on said assembly.

13. In a side frame for a railway car truck, tension and compression members and spaced columns defining therewith a bolster opening and spaced window openings, coil springs seated on said tension member beneath said openings, openings in said columns aligned longitudinally of said frame, a plate spring assembly comprising superposed relatively movable abutting plates extending through said column openings and supported on said coil springs, and means at the ends of said frame abutting said assembly whereby said plates are retained in normal assembled relationship.

14. In a railway car truck, a side frame comprising spaced columns partly defining a bolster opening, resilient means in said opening comprising a group of coil springs supported on said frame and a plate spring assembly mounted on said group, said assembly consisting of a plurality of superposed relatively movable plates abutting each other throughout their length, means on said frame for retaining said plates in assembly, and a bolster mounted on said assembly.

15. A truss side frame having tension and compression members merging adjacent their ends, spaced columns integrally formed with said members to form a bolster opening and spaced window openings, abutment means in said tension member adjacent opposite ends of the frame, vertical openings in said columns aligned with said abutment means, spring seats on said tension member beneath said abutment means and at spaced points below said bolster opening, and a plurality of webs joining the inboard and outboard walls of said tension member intermediate said spring seats.

16. A truss side frame having tension and compression members merging adjacent their ends, spaced columns integrally formed with said members to form a bolster opening and spaced window openings, abutment means in said tension member adjacent opposite ends of the

frame, vertical openings in said columns aligned with said abutment means, and spring seats on said tension member beneath said abutment means and at spaced points below said bolster opening, said tension member having maximum depth adjacent said abutment means and minimum depth beneath said bolster opening.

17. In a railway car truck of quick wheel change type, a truss side frame having tension and compression members and spaced columns forming therewith a central bolster opening and spaced window openings, coil springs supported on said tension member below each of said openings, a plate spring assembly supported at spaced points on said coil springs, and a bolster having an end projecting into said bolster opening and supported on said plate spring assembly, said end having inboard and outboard jaw means confining said assembly, said outboard jaw means being of limited depth whereby said end may be raised in said opening and removed therefrom during a quick wheel change.

18. In a railway car truck, a side frame comprising a bolster opening, resilient means comprising a plate spring assembly, said assembly consisting of a plurality of superposed relatively movable plates abutting each other throughout their length, means on said frame for retaining said plates in assembly, a bolster in said opening mounted on said assembly, and a spring group on said frame supporting said assembly and permitting relative vertical movement thereof with respect to said frame.

19. In a railway car truck, a side frame comprising spaced columns partly defining a bolster opening, openings in said column, spaced resilient means mounted on said frame, a plate spring assembly supported on said means and comprising a plurality of superposed relatively movable abutting plates projecting at opposite ends thereof through said column openings, means at the end of said frame for restraining said plates against longitudinal movement with respect thereto, said plates being restrained against lateral movement by abutment with inboard and outboard edges of said column openings, and a bolster in said bolster opening mounted on said assembly.

20. In a railway car truck, a side frame comprising tension and compression members and spaced columns defining therewith a bolster opening and spaced window openings, coil springs seated on said tension member beneath said openings, longitudinally aligned openings in said columns, abutment means at each end of said frame, a plurality of identical parallel plate springs seated on said coil springs extending through said column openings and abutting said means, and a bolster end seated upon said plate springs, said plate springs being held in assembled relationship by their abutment with said means and with the inboard and outboard edges of said column openings.

21. In a railway car truck, a side frame comprising tension and compression members and spaced columns defining therewith a bolster opening and spaced window openings, coil springs seated on said tension member beneath said openings, openings in said columns aligned longitudinally of said frame, a plate spring assembly comprising identical superposed abutting plates extending through said column openings and supported on said coil springs, means at the ends of said frame abutting said assembly whereby said plates are retained in normal as-

sembled relationship, and a bolster end supported on said assembly.

22. In a railway car truck, a side frame comprising tension and compression members and spaced columns defining therewith a bolster opening and spaced window openings, coil springs seated on said tension member beneath said openings, openings in said columns, a plate spring assembly comprising identical superposed plates extending through said column openings and supported by said coil springs, movable means confining the ends of said plate springs and supported on certain of said coil springs, and a bolster end supported on said assembly.

23. In a railway car truck, a side frame comprising tension and compression members and spaced columns defining therewith a bolster opening and spaced window openings, coil springs seated on said tension member beneath said openings, openings in said columns aligned longitudinally of said frame, abutment means slidably supported from said frame on certain of said coil springs, a plate spring assembly ex-

tending through said column openings and seated on said abutment means and on other of said coil springs, and a bolster end supported on said assembly.

24. In a railway car truck of quick wheel change type, a truss side frame comprising tension and compression members and spaced columns forming therewith a bolster opening and spaced window openings, coil springs supported on said tension member, a plate spring assembly supported on said coil springs, and a bolster comprising an end received within said bolster opening and supported on said plate spring assembly, said bolster end having inboard and outboard jaw means confining said assembly, said outboard jaw means having a depth less than the clearance between the top of said bolster end and the overlying portion of said compression member whereby said end may be elevated in said bolster opening and removed therefrom during a quick wheel change.

ALFRED H. OELKERS.
